RADIATOR OVERFLOW REGULATOR

Jesse E. Eshbaugh and Nelson Walker, Flint,
Mich., assignors to General Motors Corporation,
Detroit, Mich., a corporation of Delaware

Application February 26, 1938, Serial No. 192,778

9 Claims. (Cl. 277—61)

To reduce loss of engine cooling liquid there is currently in favor the use of overflow control valving for closing automobile engine cooling systems. The loss is partly of vapors especially when a low boiling point solution is employed and also of liquid due to overheating and surging of the system contents from the engine jacket into the present day small capacity vented inlet tank of the radiator assembly.

10. A pressure relief valve closing the overflow vent conserves the cooling medium and enables operation of the system under slight pressure which raises the boiling point of the liquid and increases the rate of heat dissipation, the valve being set to relieve excess pressure and prevent bursting strains on the weaker parts of the system and leakage at the hose connections and water pump packings. To avoid subnormal pressures incident to a drop in system temperature 20 or other causes, it is desirable that provision be made to bleed air into the system for the relief of internal depression.

It is an object of the present invention to provide an improvement in the construction and 25 operation of overflow regulators. The improved structure is one comprising a few simple low cost parts which can be easily applied as an accessory device to the discharge end of the usual overflow pipe without otherwise disturbing or modifying the existing system. As a commercial unit free of complication it is proposed to provide as a preferred embodiment, an overflow pipe fitting to which is secured a valve cage with a valve seat interposed between the cage and fitting and 30 an integrally formed elastic skirt extending into and lining the wall of the fitting in overlapping relation to an air intake port or opening in the wall. By reason of the snug fit of the lining to the wall the air intake port is closed normally, 35 any internal pressure tending to expand the skirt into closer sealing contact with the wall so that internal pressure will be wholly under control of the outwardly opening valve housed by the cage. On the other hand internal depression and atmospheric pressure acting on the skirt will contract or deform the elastic material and thereby 40 break the seal for the entrance of air through the port until substantial balance is established.

The arrangement and operation will be better understood upon reference to the accompanying drawing wherein Figure 1 is a side elevation showing an engine cooling system to which the invention has been applied; Figure 2 is a fragmentary view of the closed filler spout, a portion being shown in section as on line 2—2 of

Figure 1; Figure 3 is a sectional view of the valve unit taken substantially on line 3—3 of Figure 1; Figure 4 is a detail section showing the vacuum relief valve in open position; Figure 5 is a perspective view illustrating a modification.

In the drawing the reference numeral 1 indicates a water cooled engine having an outlet hose connection 2 with the inlet tank 3 on the radiator core 4. The radiator outlet tank 5 has a hose connection 6 with the inlet to the pump 7 mounted on the front face of the cylinder block 1. The pump is driven from the engine crankshaft by a belt 8 which also operates the fan 9 for drawing air through the core 4. Associated with the top tank 3 is a filler spout 10 closed by a removable cap 11 carrying a sealing gasket 12.

The structure thus far described constitutes a conventional engine cooling system which also has an overflow vent pipe 13 leading from the upper region of the top tank 3 down the side of the radiator assembly so that any discharge through the pipe will leave the system at a low point. This discharge end of the overflow pipe affords a convenient location for an accessory valve device and in the drawing the structure 25 of the valve device is shown in detail in Figure 3. It includes a housing formed of a pair of interconnected tubular members 14 and 15. The member 14 affords a fitting to be aligned with and secured to the end of the overflow pipe 13. 30 A satisfactory connection may be had through the use of a rubber tube or coupling hose 16 fitted over the adjacent ends of the tubes 13 and 14. Intermediate its ends the tube 14 is of an enlarged diameter as at 17 and is provided with 35 one or more ports or openings 18. The enlarged portion 17 terminates in an annular flange or shouldered portion 19 against which bears a valve seating washer 20 of elastic deformable material such as rubber or Duprene, carrying as an integral extension thereof, a tapered annular wall or skirt 21 which lines the interior of the enlarged tubular wall 17 in overflapping and sealing relation to the ports 18.

The washer 20 is held against the shoulder 45 19 by a flanged ring 22 against which bears an annular flange 23 on the tubular member 15, the parts being held in assembled relation by peening, over the flange 23, the end 24 of a cylindrical wall 25 dependent from the flange 19. 50 The rim of the washer 20 is thus retained within an annular chamber formed between the tubular elements 14 and 15 and its central opening is closed by a ball check valve 26 seated on the washer by a coil spring 27. The tubular element 55

15 thus constitutes a retainer or cage for the valve 26 and its spring 27, the bottom wall of the cage having a depression 28 to locate the remote end of the spring. The wall of the depression 28 may be apertured as at 29 and additional openings 30 may be cut in the wall of the tube 15 for discharge of any leakage past the ball valve 26.

In the normal operation of the system the ball 26 closes the overflow and causes the system to operate under a slight pressure dependent upon the resistance of the valve seating spring 27. Satisfactory operation will be had if the spring is so selected that the ball will open at three or four pounds internal pressure to relieve pressure in excess of this amount. The openings 18 inwardly of the valve are closed by the snug fit of the skirt 21 to the interior surface of the wall 17 and any internal pressure pushes the skirt wall outwardly and makes the seal more effective. Should an internal vacuum exist the external air pressure will break the seal by contracting the skirt 21 or otherwise deforming it as shown in Figure 4 so that air enters through the openings 18 and passes upwardly into the overflow pipe. To facilitate the inward bending of the tapered end portion of the skirt the peripheral surface of the skirt in alignment with the openings 18 may be provided with an annular groove 31 which reduces the width of the wall at this point and allows a distribution of the pressure throughout the circumference of the skirt.

In the modification illustrated in Figure 5 the usual overflow vent may be omitted or plugged and the filler spout 32 closed by an elastic tube 33 whose lower end is of an outside diameter to fit snugly within the interior of the spout 32. The other end of the tube 33 is pinched together by a spring member 34 of U-shape in cross section 40 so that the system is sealed. Internal pressures will expand the flexible tube 33 in tight engagement with the filler spout and when a predetermined temperature is reached the upper end of the tube will be opened by the spreading apart 45 of the legs of the spring member 34. On the other hand suction internally of the system will break the seal between the spout 32 and the flexible wall 33 for passing air into the system. Positioning lugs or buttons as at 35 may be carried 50 by the flexible wall for engagement with the upper edge of the spout 32 and ordinarily the frictional fit of the parts will be sufficient to prevent accidental dislodgment of the closure. However, as a further precaution against displacement 55 the spout may be provided with bayonet slots to receive the buttons 35 and retain the removable closure in place.

We claim:

1. In a closed cooling system, a valved conduit 60 including a rigid wall portion, an elastic wall portion having one end telescopically fitted to said rigid portion and adapted to be forced away from the rigid wall portion for passing air into the conduit upon internal sub-atmospheric conditions and outwardly opening pressure relief valve means for closing the other end portion of said elastic wall portion.

2. In a closed cooling system, an elastic overflow conduit member, pressure relief means 70 gaging said member, a rigid conduit member externally and telescopically fitted to the elastic member inwardly of said pressure relief means and against which said elastic member bears snugly in the presence of internal pressure and

from which the elastic member separates under the force of external pressure for bleeding air into the system.

3. In a device of the character described, a tubular element having a shouldered portion, a valve seating washer in sealing engagement with said shoulder, a pressure relief valve seating on said washer to seal a central aperture therethrough and an elastic skirt extending from the washer into said tubular element and normally 10 yielding sealing a port in the wall of the tubular element.

4. In combination, an open ended casing, a removable closure therefor, comprising a rubber tube fitted to said spout and distended by internal pressure into sealing contact therewith, said seal being broken by external pressure acting on the tube to deform the same, and spring clamp means squeezing the end of the tube to close the same, and being adapted to yield for the relief 20 of internal pressure.

5. A vent valve assembly of the character described, including a housing having an intermediate shoulder and tubular portions projecting in opposite directions from the intermediate shoulder, a valve seating washer of elastic deformable material associated with said shoulder, a spring pressed outwardly opening valve seating on said washer and being enclosed in one of the tubular portions, and a skirt formed integrally with said washer and telescopically fitted to the interior wall surface of the other tubular portion to constitute an inwardly opening closure valve for a port in the wall.

6. A radiator overflow valve, including a valve seating washer having an extended skirt of elastic deformable material, a tubular member fitted to said skirt and having an opening therein normally closed by the skirt, an outwardly opening valve seated on said washer, a valve seating 40 spring, and a tubular member enclosing said valve and seating said spring, said tubular members having cooperating outturned flanges peened one over the other and affording an annular recess to receive and locate said washer.

7. A radiator overflow valve including a conduit terminating in a shouldered portion, a valve seating washer bearing on said shouldered portion and having a skirt of elastic deformable material extended into said conduit in close fitting 50 relation to the interior surface thereof for normally closing a port in the conduit wall, a retainer ring for said washer, a valve cage bearing on said ring and secured to said shouldered portion and a spring pressed valve enclosed by the 55 cage and seated on said washer.

8. In a radiator overflow valve assembly, a conduit member, outwardly opening valve means for said member, a valve comprising a lining of elastic deformable material affording a seat at one 60 end for said valve means and being fitted to said member inwardly of said valve means and provided with an annular groove on its peripheral surface in alignment with an opening in the wall of said conduit member.

9. In a radiator overflow valve assembly, a conduit having an intake opening in the wall thereof, a rubber bushing valve fitted into the tube over said opening and an outwardly opening check valve seating on the end of the rubber 70 bushing outwardly of said intake opening.
